UNITED STATES PATENT OFFICE

SAMUEL L. CROWE, OF SEYMORE, INDIANA, ASSIGNOR TO SEYMORE MANUFACTURING COMPANY, INCORPORATED, OF SEYMORE, INDIANA, A CORPORATION OF DELAWARE

SCYTHE SNATH FASTENER

Application filed May 12, 1930. Serial No. 451,599.

This invention relates to agricultural implements, and more particularly to fastening devices for securing scythe blades to snaths, and has for one of its objects to provide an improved device of this character which permits firm securement of the scythe blade to the snath in various positions of angular adjustment, and which is simple, durable and capable of being quickly and easily manipulated to permit removal and replacement of the scythe blades. Another object is to provide an improved fastening device which is adapted to firmly and positively secure the scythe blade to the snath without subjecting the wood of the snath to any crushing strains, and which is also designed to absorb the twisting strains at the lower end of the snath. A further object is to provide an improved fastening device, so constructed as to reinforce and prevent injury to the lower end of the snath and which also serves to enclose and completely protect the end grain surface of the snath against contact with the ground and the action of the elements. It consists in certain features and elements of construction, herein shown and described, and indicated by the claims.

To acquaint those skilled in the art with the manner of constructing and practicing the present invention, I shall now describe a particular embodiment of the same, in connection with the accompanying drawings, in which,

Figure 1 is a perspective view of the lower end of the snath provided with a fastening device embodying the present invention.

Figure 2 is a view in side elevation.

Figure 3 is an end view of the snath with the fastening device applied thereto.

Figure 4 is a transverse section taken substantially as indicated at line, 4-4, on Figure 2, showing the rabbeted connection between the fastening device and the snath.

Figure 5 is a perspective view of the eye bolt used in connection with the fastening device.

Figure 6 is a perspective view of the shank portion of a scythe blade.

Referring now in detail to the drawings:

The numeral, 10, indicates a snath of usual construction, preferably made of wood, and having its lower end portion provided with a flattened surface indicated at 11, on which is rigidly secured a plate, 12, by means of a rivet or bolt, as indicated at 13, extending transversely through the snath. The upper exteriorly exposed surface of the plate, 12, is preferably formed flat to provide a seat for the shank portion, 15, of a scythe blade (not shown). Desirably the plate, 12, is formed as a casting and has integrally associated therewith a head or cap, 17, substantially annular in form, having a skirt or band portion, 18, which is internally tapered as indicated at 19, for a drive fit onto the reduced end portion, 10^a, of the snath. The cap fully encases said lower end portion of the snath and thereby serve as a reinforcement for preventing splitting or injury thereof, while at all times absorbing the lateral thrust imparted by the scythe blade when the device is being used.

The top portion of the cap, 17, is of substantial thickness (as may be seen in Figure 2) and is provided with a pocket or recess, 20, dimensioned to insure clearance and accommodate a loop or eye bolt, 21, adapted to be disposed therein with its shank portion, 22, extending transversely through said top portion of the cap and engaged by a clamping nut, 23, on the side opposite the recess. The cap, 17, on opposite sides of the recess is preferably formed with a flat surface flush with and serving as a continuation of the flat surface of the seating plate, 12, against which seat the tang or shank, 15, of the scythe blade is adapted to be secured by the eye-bolt, 21. In assembling or securing the scythe blade to the fastening device the shank thereof is inserted through the loop or eyebolt, 21, and has its laterally projecting tang, 15^a, registered in one of the series of apertures, 12^a, in said plate, 12; then upon tightening of the clamp nut, 23, the eye-bolt will draw the shank, 15, firmly against its seat on the plate and cap, 17, and will positively hold it in such position. A resilient lock washer, 24, keeps the nut from working loose. The snath may be formed with re-

cesses, 10^b, in registration with the apertures, 12^a, of the plate so as to accommodate a relatively long projection, 15^a, of the scythe blade shank. When the eye-bolt, 21, is loosened to release the shank, 15, the latter may be quickly adjusted to register its locking projection, 15^a, with any of the apertures of the series for obtaining a desired angular relation of the scythe blade to the snath. 10 By merely turning the nut, 23, the eye-bolt, 21, may be caused to release or firmly engage the shank of the scythe blade to permit its free and easy removal or replacement.

It will be observed that the actual fastening element herein indicated as the eye-bolt, 21, is carried entirely out of direct engagement with the snath proper, and as may be seen in Figure 2 of the drawings, it is disposed beyond the end of the snath so that 15 the snath is wholly relieved of the crushing stresses incident to clamping the shank of the scythe blade to the plate, 12. To further relieve any strain on the securing bolt, 13, and to prevent turning of the fastening 20 element on the lower end portion of the snath, I preferably provide the marginal edges of the plate, 12, with inclined downwardly projecting flanges, 12^b, which are rabbeted into the snath proper, as may be 25 seen in Figure 4 of the drawings, thus firmly and securely holding the fastening device in place on the snath. This arrangement manifestly avoids undue strain on the parts and naturally extends the period of usefulness 30 of the implement.

By fully encasing the lower end of the snath by the cap, 17, this portion of the snath is at all times protected against injury and reinforced against splitting by reason of 35 encountering objects, as well as by constant engagement with the earth, while the implement is being used, and in addition this construction precludes moisture from coming in direct contact with the end surface of the 40 lower end of the snath and causing deterioration thereof and shortening of its useful life.

Although I have shown and described one form in which my invention may be embodied, it is to be understood that the proportion and arrangement of parts may be varied without departing from the scope and spirit of my invention. I therefore do not wish to be limited to the specific construction illustrated in the drawings, except 45 as indicated by the claims.

I claim:

1. In combination with a snath, a plate rigidly secured to the lower end thereof and having an exposed surface formed to serve 50 as a seat for the tang of a scythe blade, a cap rigidly associated with the plate and constructed to completely encase the extreme lower end of the snath, and means associated with the cap, constructed to engage said 55 tang of the scythe blade independently of

the snath for securing it in place on the plate.

2. In combination with a snath, a plate rigidly secured to the lower end thereof and having an exposed surface formed to serve 70 as a seat for the tang of a scythe blade, a cap rigidly connected with the plate and constructed to completely encase the extreme lower end of the snath, and means associated with the cap and disposed beyond the 75 end of the snath for engaging the tang of the scythe blade and clamping it against the seat of the plate.

3. In the construction defined in claim 2, said means comprising an eye-bolt disposed 80 transversely of the snath, and said cap being recessed to accommodate the eye-bolt therein.

4. In combination with a snath, means for securing a scythe blade tang to the snath 85 including an eye-bolt, a fitting secured to the lower end of the snath and including a cap encasing said end portion of the snath together with a pocket formed on the outer end of the cap beyond the snath, said pocket 90 opening laterally and being dimensioned to receive the eye of the eye-bolt for clamping the tang of a scythe blade, the bottom of the pocket being apertured and the shank of the bolt extending through the aperture to permit application of an adjusting nut thereto 95 outside the pocket.

5. In combination with a snath, means for securing a scythe blade tang thereto including an eye-bolt, a fitting secured to the lower 100 end of the snath and including a cap encasing the end portion of the snath, said cap having two end walls spaced apart to form a pocket beyond the end of the snath, said pocket opening laterally and being dimensioned to receive the eye of the eye-bolt for clamping the tang of the scythe blade, the shank of said eye-bolt extending through an aperture in the bottom of the pocket and a plate extending from the edge of the 105 pocket nearest the end of the snath and overlying the latter to support the tang of the blade in the plane of the pocket opening.

In testimony whereof, I have hereunto set my hand at Seymour, Indiana, this 8th day 110 of May, 1930.

SAMUEL L. CROWE.
